US00D780334S

(12) United States Design Patent (10) Patent No.: US D780,334 S
(45) Date of Patent: * Feb. 28, 2017

(54) PORTION OF A SLAB

(71) Applicant: Cambria Company LLC, Eden Prairie, MN (US)

(72) Inventors: Martin E. Davis, Excelsior, MN (US); Jon Louis Grzeskowiak, II, Prior Lake, MN (US); Summer Lane Kath, Eden Prairie, MN (US)

(73) Assignee: Cambria Company LLC, Eden Prairie, MN (US)

() Term: 15 Years

(21) Appl. No.: 29/505,227

(22) Filed: Aug. 3, 2015

(51) LOC (10) Cl. 25-01

(52) U.S. Cl.

USPC D25/149; D5/44

(58) Field of Classification Search

USPC D25/138, 140, 149, 151, 164, 199; D5/5, D5/8, 20, 43, 44, 64; 428/171, 364, 540; D6/597; D19/4, 28

CPC B44F 9/04; D21H 27/04

CLAIM

The ornamental design for a portion of a slab, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a top plan view of a portion of a slab, showing our new design. The depicted surface of the portion of a slab is flat.
